UNITED STATES PATENT OFFICE

2,297,490

PAPER GUIDE AND FEED FOR
TYPEWRITERS

Hans Martin and Leopold Gebert, Erfurt, Germany; vested in the Alien Property Custodian

Application April 7, 1941, Serial No. 387,288
In Germany July 24, 1939

4 Claims. (Cl. 197—138)

This invention relates to paper carriages of typewriters and the like and particularly to paper guide and feeding devices thereof.

It is an object of the invention to provide a paper guide and feed device which will insure the even and exact feed of both thin and thick papers in single or multiple layers.

Another object of the invention is to provide a paper guide and feed construction for typewriters and the like in which the guide plate or apron which underlies the platen and the feed rollers associated therewith are constructed and assembled as a unit which may be mounted in and removed as such from the paper carriage quickly and easily after the platen is removed, thereby facilitating access to all parts of the carriage by a person having little knowledge of typewriter construction.

Another object of the invention is to provide a paper guide and feed construction which will permit insertion and proper feeding of different numbers or thicknesses of sheets at opposite sides of the carriage at the same time.

Another object of the invention is to provide a paper carriage in which the paper guide apron and feed rollers are carried by a single shaft adapted to be mounted beneath and parallel to the platen whereby the mounting of the shaft correctly positions the guide and feed rollers in the carriage frame and in which a plurality of platen engaging feed rollers are mounted on levers carried by said shaft and capable of independent action in accommodating themselves to the thickness of the paper fed around the platen.

Another object of the invention is to provide a novel mounting connection between the paper guide apron and the feed roller mounting levers wherein the levers are mounted in pairs in opposed relation on a single shaft and at their outer ends are articulated to the paper guide apron and in which the feed roller levers are held in position on the mounting shaft by springs which serve also to rock the levers into position to press the feed rollers against the platen.

Another object of the invention is to provide a novel construction and method of mounting the feed roller carrying levers on a single supporting shaft, in which the levers in pairs are provided with oppositely disposed bearing seats open on one side so as to be assembled directly on the shaft from the side thereof and held in assembled engagement with the shaft by the springs which also press the feed rollers against the platen.

Another object is to provide means for spread-

ing the levers to release the feed rollers from engagement with the platen.

Other objects and advantages of the invention will be apparent from the following detailed description of the invention in relation to the accompanying drawing which illustrates a preferred constructional embodiment of the invention by way of example. In the drawing:

Fig. 1 is a perspective view of the paper guide and feed assembly detached from the carriage,

Fig. 2 is a perspective view from above of the paper carriage with the platen and paper guide unit removed,

Fig. 3 is a sectional view on the line 3—3 of Fig. 2, with the paper guide in operative position in the carriage,

Fig. 4 is a disjointed detail view of the mounting levers for the feed rollers and guide apron, and

Fig. 5 is a detail of one of the end bearing supports for the supporting shaft of the paper guide and rock shaft for releasing the feed rollers.

Referring more particularly to the drawing, in which all standard parts not necessary to an understanding of the invention have been omitted, 10 indicates a platen roller which is removably journaled on the paper carriage 11 in advance of an upstanding paper table 12 mounted thereon. The paper table 12 is provided with vertical ribs 13 adjacent the ends thereof which facilitate passage of the lower edge of the paper onto an apron 14 which, in operative position, extends from the lower portion of the table 12 around the underside of the platen 10 to guide the paper therearound. The rear portion of the apron 14 is dimensioned and curved backwardly to engage the lower portion of the table 12 at the lower ends of the ribs 13.

The guide apron 14 is provided with a row of front apertures 15 and rear apertures 16 for front and rear feed rollers 17 and 18, respectively, spaced along the length of the apron, which rollers contact the platen 10. The apron 14 and feed rollers 17 and 18 are supported by spaced pairs 45 of lever arms 19 and 20 mounted on a shaft 21. The front feed rollers 17 are mounted on pivot pins 22 which extend through apertures 23 in the ends of the forwardly extending front levers 19 of each pair and through bracket ears 24 carried by the apron 14 at the ends of the respective apertures 15. The pins 22 and bracket ears 24 provide an articulated connection between the ends of the levers 19 and the front portion of the apron 14.

55 The rear feed rollers 18 are mounted on pivot

pins 25 which extend through apertures 26 in the ends of the rearwardly extending rear levers 20 and through slots 27 in bracket ears 28 carried by the apron 14 at the ends of the respective apertures 16. The pins 25 extending through the slots 27 in the bracket ears 28 provide an articulated connection between the levers 20 and the rear portion of the apron and the slots 21 are arranged so that the pins can ride therein to permit relative movement between the rear feed rollers and the apron, necessary to effect release of the rollers from the platen as hereinafter described.

Referring more particularly to Figs. 3 and 4, each front lever arm 19 is formed with a downwardly opening bearing eye or notch 29 which fits the shaft 21 and with a rearwardly extending arm 30 having an upstanding stud 31 at its terminus. Each lever arm 20 is formed with an upwardly opening bearing eye or notch 32 which fits the shaft 21 and with a depending stud 33 disposed in opposed relation to the stud 31 on arm 30 of lever 19 when a pair of the levers are assembled side by side on the shaft 21. A coiled compression spring 34 mounted on the studs 31 and 33 yieldingly rocks the levers in opposite directions to retain them on the shaft and to press the feed rollers against the platen. The levers 19 are provided with an upwardly directed, rearwardly extending projecting portion 35 which bears against the side of the respective levers 20 to steady the levers against lateral tipping. The shaft 21 on which the levers are mounted is formed with spaced annular grooves 36 constituting bearing seats in which the levers are seated, the grooves being spaced apart the length of the feed rollers and serving to prevent lateral displacement of the levers on the shaft.

For the purpose of releasing the feed rollers from pressure against the platen, the levers 19 and 20 are provided with forwardly extending arms 37 and 38, respectively, which cross each other and are adapted to engage cutaway portions 39 on opposite sides of a release shaft 40 which is provided with a release lever 41 for rocking the same. Rocking the shaft 40 from the position shown in Fig. 3 forces the arms 37 and 38 apart and rocks the levers 19 and 20 about the shaft 21 against the pressure of spring 34 to retract the feed rollers from the platen.

A plurality of bearing blocks or rests 42, shown in detail in Fig. 5, are mounted at intervals along the length of the carriage frame beneath the platen position. These bearing blocks, which may be formed of sheet metal, include an upstanding web 43 provided with a bearing aperture 44 for mounting the release shaft 40 and an upwardly opening bearing notch 45 for seating the shaft 21.

From the above it will be observed that the complete paper guide and feeding unit is assembled independently of the carriage frame. In the assembly, the swinging levers 19 and 20 are fitted on the shaft 21 from opposite sides and, together with a pressure roller for each pair, are fastened to the bearing ears of the paper guide apron by the pivot pin for the feed rollers, the bearing ears being disposed between the ends of the rollers and the ends of the levers. The springs 34 are then mounted in position and hold the levers on the shaft 21. When all of the levers and feed rollers are thus mounted, the unit is inserted in the carriage frame, the release arms 37 and 38 being first slipped over the re-

lease shaft 40 which is already in position. The unit is then tipped back to seat the shaft 21 in the bearing notches 45 of the bearing blocks 42. As the unit reaches this position, the rear edge of the apron 14 engages the lower portion of the table 12 abutting the lower ends of the ribs 13 and it is positioned for cooperation with the platen. The platen 10 is then mounted in the carriage, the parts being so disposed that it presses against the feed rollers, as will be readily understood. When it is desired to remove the guide for any purpose, such as cleaning or repairing, the platen is first removed and the guide unit is merely lifted bodily out of the carriage.

In the operation of a typewriter or the like equipped with the new paper guide, movement of the release lever 41 to rock the shaft 40 causes an outward movement of the ends of levers 19 and 20 and the feed rollers carried thereby away from the platen. This movement is also transmitted to the paper guide apron through the bearing ears so that the same also moves down, uniformly enlarging the space between it and the platen. The pin and slot connection between the levers 20 and the rear bearing ears of the apron permits equalization of the paths of motion and spreading of the levers with respect to each other, which is necessary to the releasing operation.

With the unit construction of paper guide and feed according to this invention, it is possible to provide carriage frames of any length with a plurality of guide units end to end in the carriage. This is very important as it avoids the necessity of making up special feed devices for the seldom ordered, extra length carriages. In such carriages, each of the guide units has a mounting shaft equivalent in length to the apron section employed and the respective units may be separately removed and installed. However, for convenience in operation, a single release shaft extending the full length of the carriage and common to all of the guide units is preferably used.

While a preferred constructional embodiment of the invention has been shown and described by way of illustration, various modifications in the details of construction and arrangement of the parts may be resorted to without departing from the spirit of the invention within the scope of the claims.

We claim:

1. In a typewriting machine, a carriage frame, a platen removably journaled in said frame, open mouthed bearing seats on said frame beneath said platen, a shaft removably seated in said bearings, spaced pairs of lever members, the lever members of each pair extending forwardly and rearwardly and having opposed open bearing notches engaging opposite sides of said shaft, springs engaging opposed portions of the levers of each pair to urge them into gripping relation with said shaft, feed rolls journaled between the respective ends of the lever arms of adjacent pairs, and a guide apron articulated to the ends of the levers and supported thereby, said guide apron, levers, feed rollers and shaft constituting a unit assembly removable as such from the carriage after removal of the platen.

2. In a typewriter, the combination with a paper carriage having a removable platen and a paper table in fixed relation to said platen, paper guide and feed means comprising a unit assembly adapted to be mounted in said carriage beneath

said platen and removable therefrom upon removal of said platen, said unit assembly comprising a shaft, front and rear levers arranged in pairs spaced along said shaft and having oppositely opening bearing notches engaging said shaft from opposite sides thereof, springs coacting between the front and rear levers of each pair and pressing them into engagement with said shaft, feed rollers journalled at the ends of said levers and adapted to bear against said platen, and a paper guide apron pivotally connected to and supported by said front and rear levers; a plurality of open mouthed bearing supports mounted in said carriage beneath the platen for seating said shaft, a release shaft journalled in said carriage, an arm on each of said levers for engaging said release shaft, said paper guide apron having a rear edge portion adapted to contact a part of said paper table on said carriage when said unit is inserted in said carriage with the arms on said levers engaging said release shaft and said first mentioned shaft is seated in said bearings to position said paper guide apron and feed rollers for cooperation with the platen.

3. In a typewriting machine, a paper carriage frame, a platen removably journalled in said frame, open mouthed bearing members mounted in said frame beneath the position occupied by the platen; a paper guide and feed unit comprising a shaft adapted to seat in said bearing mem- 30

bers, a plurality of spaced pairs of lever members pivotally mounted on said shaft, each pair of lever members comprising a front lever and a rear lever arranged side by side and have oppositely disposed bearing notches engaging said shaft from opposite sides, a spring coacting between the levers of each pair and pressing them into engagement with said shaft, said shaft having annular grooves for seating the bearing portions of each pair to retain them against lateral displacement, feed rollers journalled at the ends of the respective lever arms, and a curved guide apron pivotally connected at spaced points to said levers and supported thereby; said paper guide and feed unit being bodily removable from said carriage after removal of said platen; a rocking cam release shaft mounted on said frame, arm members carried by said levers for engaging said cam release shaft when said unit is in operative position in said carriage frame to throw said levers away from said platen to release the pressure of the feed rolls therefrom, and means for rocking said cam release shaft.

4. A typewriting machine as defined in claim 3 in which one of the levers of each pair is provided with a widened flat bearing portion bearing on the side of the other lever.
